Primary Examiner — Lucy Lieberman(74) *Attorney, Agent, or Firm* — Kubotera & Associates, LLC(57) **CLAIM**

The ornamental design for a clock, as shown and described.

DESCRIPTION

FIG. 1 is a perspective view of a clock showing my new design; and,

FIG. 2 is a front view thereof.

The broken lines in FIGS. 1 and 2 are used to illustrate portions of the clock that do not form part of the claimed design.

1 Claim, 2 Drawing Sheets**FIG. 1**

FIG.2
